CLAIM

The ornamental design for a foldable table, as shown and described.

DESCRIPTION

FIG. 1 is a perspective view of a foldable table showing my new design;

FIG. 2 is a folded view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plain view thereof; and,

FIG. 8 is a bottom plain view thereof.

The broken lines in the drawings illustrate the portions of the design that form no part of the claim.
